TO FRANK F. COGGIN, OF SOMERVILLE, MASSACHUSETTS, AND ONE-THIRD TO R. P.
WHITCHER, OF MELROSE, MASSACHUSETTS.

GREASE-CUP PLUG.

Application filed March 25, 1922. Serial No. 546,600.

To all whom it may concern:

Be it known that I, MILTON P. McLAUGHLIN, a citizen of the United States, residing at Wakefield, in the county of Middlesex and State of Massachusetts, have invented new and useful Improvements in Grease-Cup Plugs; of which the following is a specification.

This invention relates to plugs employed to confine a lubricant, and particularly a relatively hard grease, in a grease cup carried by a moving part of a machine, such as a connecting-rod, or other parts subjected to vibration. A plug of this character is detachably secured to the grease cup by a screw-thread connection therewith. When the cup is carried by a part, such as a connecting-rod, connecting the driving wheels of a locomotive, the plug is often accidentally disengaged from the cup by the movements of the cup.

It is the object of my invention to provide simple and effective means for locking the plug to the grease cup in such manner as to prevent liability of accidental displacement of the plug.

The invention is embodied in the improvements which I will now proceed to describe and claim.

30 Of the accompanying drawings forming a part of this specification,—

Figure 1 is a side view of a plug embodying the invention, showing the locking dog projected.

35 Figure 2 is a similar view, showing the locking dog released.

Figure 3 is a section on line 3—3 of Figure 1.

Figure 4 is a perspective view of the plunger.

Figure 5 is an end view of the plunger looking toward the inner end.

Figure 6 is a sectional view, showing the plug adjusted as shown by Figure 1.

45 Figure 7 is a sectional view, showing the plug adjusted as shown by Figure 2.

Figure 8 is a perspective view of the locking dog.

Figure 9 shows the plug on a considerably reduced scale, and a portion of a connecting-rod having a grease cup with which the plug is engaged.

Figure 10 is a sectional view, showing a modification.

A grease-cup plug 12 embodying my invention, is externally threaded for engagement with the internal thread of a grease-cup or cavity, such for example, as a cup 13 in a locomotive connecting-rod 14, and is provided with a lateral guiding orifice 15, 60 intersecting a portion of the external screw thread. A locking-dog 16 is movable in said orifice, and is composed of a material such as brass, adapted to be indented by said internal thread without mutilating the latter. 65 The dog has a substantially flat outer end face of sufficient area to contact with a plurality of convolutions of the internal thread, and adapted, when forced outward, to be indented by the portions of said convolutions 70 with which it contacts. The plug is provided with means for projecting the dog 16 into locking engagement with the internal thread, to prevent the unscrewing of the plug from the cup, said means being adapted to release the dog from said locking engagement and permit the unscrewing of the plug. 75

The preferred embodiment of the invention shown by Figures 1 to 9, inclusive, includes means acting automatically to normally hold the dog projected into locking engagement with the cup thread, said means being operable to release the dog. 80

In this embodiment of the invention, the 85 plug 12 is provided with a cavity 18, open at the outer end of the plug, and closed at the inner end, as shown by Figures 6 and 7, the guiding orifice 15 being a slot opening into the cavity. The dog 16 is formed to 90 project partly into the cavity 18, and is provided with an ear 19, arranged to bear on the wall of the cavity and limit the outward movement of the dog.

20 represents a plunger having a sliding 95 fit in the cavity 18, and normally pressed outward and yieldingly held in the position shown by Figures 1, 3, 6 and 9, by a spring 21, interposed between the closed inner end of the plug and the bottom of a socket 22 100 in the plunger. One side of the plunger has a recess 23, provided with an inclined face portion 24, which is formed to bear on the correspondingly inclined back of the dog 16.

The plunger is provided with a pin or stud 24^a, projecting from one side of the plunger into an orifice 25 in the plug. Said orifice has a cam-shaped wall portion 25^a, the purpose of which will presently appear. The 5 spring 21 normally holds the pin 24 against the outer side of the orifice 25, as shown by Figures 1 and 3, the plunger being, therefore, normally held in a raised position by 10 the spring. The arrangement is such that when the plunger is raised, its inclined face 24 acts on the dog 16 to force the latter outward to its internal thread-engaging position, shown by Figures 1 and 6. When the 15 plunger is pressed inward, the position of the inclined face 24 is so changed that the dog is released from its thread-engaging position, and is free to move inwardly to the inoperative position shown by Figures 2 20 and 7.

The plunger 20 has a head 27, formed to be engaged by a wrench. When the plunger is raised by the spring the pin 24^a is so related to the cam-shaped portion 25^a that a 25 partial rotation of the plunger in the direction of the arrow α (Figure 1), will cause an inward movement of the plunger, the pin 24 being guided by the cam-shaped portion until it reaches the position shown by Figure 2. The movement thus imparted to the 30 plunger releases the dog 16 from its operative position. A continuation of the turning movement of the plunger, after the pin reaches the position shown by Figure 2, 35 causes the pin to turn the plug in the same direction, the plunger and pin, therefore, constituting means for screwing the plug into the grease-cup 13. The dog remains released from its operative position while the 40 plunger is being turned. When the force which turned the plunger is removed, the 45 spring 21 forces the plunger outward, so that the dog is forced to its operative or locking position, by the spring acting through the plunger, the spring being suitably stiff to enable it to press the dog firmly against the internal thread of the grease cup, and prevent rotation of the plug, until the 50 plunger is pressed inward and releases the dog.

When the cup 13 is charged with grease, the plug may be screwed into the cup to force grease to the bearing, by a wrench applied to the head 27, the dog being released 55 by this operation. When the wrench is removed, the spring forces the plunger outward, so that the plug is automatically locked by the dog.

The plunger is provided with a recess 30, 60 beside the inclined face 24, the object of this recess being to facilitate the assemblage of the parts. The dog is inserted in the guiding slot 15, and held with its ear 19 bearing on the internal surface of the plug. The 65 plunger is then inserted in the plug, the re-

cess 30 being in alinement with the dog, so that the back of the dog enters the recess. The plunger is then given a partial rotation, to move the inclined face 24 into contact with the back of the dog. 70

Figure 10 shows an embodiment of the invention in which the dog is not moved automatically to its locking position. In said embodiment 31 represents the plug provided with an external screw-thread, adapted to 75 engage an internal thread in a grease cup. The plug is provided above the thread with a wrench-engaging head 32, and is also provided with a longitudinal tapped orifice 33, and with a plurality of lateral guide orifices 80 34, extending outwardly from the longitudinal orifice and intersecting portions of the external thread. With the internal thread of the longitudinal orifice 33 I engage a threaded rod 35, which is provided with a 85 conical portion 36, between the lateral orifices 34. In said lateral orifices are loosely inserted locking-dogs 37, of brass, or other like material, the inner ends of which contact with the conical portion 36. Said dogs 90 having substantially flat outer end faces adapted to be indented by the portions of the internal thread with which it contacts. The arrangement is such that inward endwise movement of the rod 35 causes the conical portion 36 to simultaneously project the locking-dogs 37 into locking engagement with the internal thread of a grease cup with which the plug is engaged, the length of the locking-dogs being such that when the 100 rod 35 is raised, the locking-dogs are released from pressure on the internal screw-thread of the grease cup. 95

The subject-matter of Figure 10 is shown in my pending application, filed June 14, 105 1921, Serial No. 477,425, of which this application is a continuation in part.

I claim:

1. A grease-cup plug externally threaded for engagement with the internal thread of a grease cup, and provided with a lateral guiding orifice intersecting a portion of the screw-thread, a locking-dog movable in said orifice, and composed of a material adapted to be indented by said internal thread without mutilating the latter, said dog having a substantially flat outer end face, and means for forcing the dog outward to cause the indentation of said end face by the said internal thread, so that the dog has a locking engagement with the internal thread, said means being adapted to release the dog from said locking engagement. 115

2. A grease-cup plug externally threaded for engagement with the internal thread of a grease cup, and provided with a lateral guiding orifice intersecting a portion of the screw-thread, a locking-dog movable in said orifice, and composed of a material adapted to be indented by said internal thread with- 120

out mutilating the latter, said dog having a substantially flat outer end face, and automatic means normally forcing the dog outward to cause the indentation of said end face by the said internal thread, so that the dog has a locking engagement with said thread, said means being operable to release the dog from said locking engagement.

3. A grease-cup plug externally threaded and provided with a cavity which is open at the outer end, and with a lateral guiding orifice intersecting a portion of the screw thread, a locking-dog movable in said orifice, and projecting into the cavity, a plunger 10 movable in said cavity, a spring exerting an outward pressure on the plunger, the plunger being provided with an inclined bearing face, whereby the dog is projected to a locking position, when the plunger is moved outward by the spring, the dog being releasable from its locking position by an inward movement of the plunger.

20 4. A grease-cup plug externally threaded and provided with a cavity which is open at the outer end, and with a lateral guiding orifice intersecting a portion of the screw

thread, a locking-dog movable in said orifice, and projecting into the cavity, a plunger movable in said cavity, a spring exerting an outward pressure on the plunger, the plunger being provided with an inclined bearing face, whereby the dog is projected to a locking position, when the plunger is moved outward by the spring, the dog being releasable from its locking position by an inward movement of the plunger, the plunger being provided with a laterally projecting pin, and the plug with a pin-receiving orifice formed to cooperate with the pin in imparting rotary movement from the plunger to the plug, the plunger being formed at its outer end to be engaged by a tool.

5. A grease-cup plug substantially as specified by claim 4, the said orifice being provided with a cam-shaped wall portion, 45 formed to cooperate with said pin in moving the plunger inward to release the dog when the plunger is turned to screw the plug into a grease cup.

In testimony whereof I have affixed my signature.

MILTON P. McLAUGHLIN.
